UNITED STATES PATENT OFFICE.

KNEELAND T. SIMONS, OF HARTFORD, WISCONSIN, ASSIGNOR OF ONE-THIRD TO DAVID C. CLARK AND ONE-THIRD TO RANDOLPH SIMONS, OF HARTFORD, WISCONSIN.

HUB-CAP.

1,101,150.

Specification of Letters Patent. Patented June 23, 1914.

Application filed July 5, 1913. Serial No. 777,398.

To all whom it may concern:

Be it known that I, KNEELAND T. SIMONS, a citizen of the United States, and resident of Hartford, in the county of Washington and State of Wisconsin, have invented certain new and useful Improvements in Hub-Caps; and I do hereby declare that the following is a full, clear, and exact description thereof.

10 My invention consists in what is herein particularly set forth with reference to the accompanying drawings and pointed out in the claim of this specification, its object being to provide for simple, economical capping of hubs, especially the hubs of motor-vehicle wheels, the caps being readily removable but not automatically detachable.

Figure 1 of the drawings represents a side elevation of the outer shell-member of the hub of a motor vehicle wheel and a removable cap therewith in accordance with my invention, the cap being partly in section on the plane indicated by line 1—1 in Fig. 2, a groove-engaging pin of the cap being also shown in section. Fig. 2 of the drawings represents a transverse section of said hub-member and cap, the plane of the section being indicated by line 2—2 in Fig. 1.

Referring by numerals to the drawings, 30 indicates an outer hub-member having a cylindrical extremity thereof provided with diametrically opposite and outwardly open curvilinear peripheral grooves 4 that alternate with similarly disposed racks 5 also provided on the periphery of said extremity of the hub. Fitting the cylindrical end of the hub-member is a cap 6 provided with inwardly extending rigid pins 7 that engage the aforesaid grooves, and hung in inner recesses 8 of the cap are rack-engaging pawls 9 under pressure of springs 10 arranged in said recesses. Pivotal shackled to ends of the pawls and guided in apertures of the hub member are outwardly projecting push-pins 11, the shackle-connections serving to prevent cramping of said pawls or pins.

In practice the disengaged cap is positioned to have the pins 7 thereof register in the outer ends of the hub-grooves 4 and said cap turned on the hub until stopped by the shoulder 12 of the same. As this operation takes place, there is slip of the spring-controlled pawls 9 over the racks 5 of the hub until the cap is full on said hub, whereupon there is an automatic engagement of said pawls with said racks to prevent automatic detachment of said cap. To remove the cap, the push-pins 11 are operated, to disengage the pawls 9 from the racks 5, and said cap turned in the proper direction to have its pins 7 clear the grooves 4 of the hub.

While I have shown a preferred construction and arrangement of parts it is within the scope of my invention, as herein claimed, to omit one of the hub-grooves and racks as well as the corresponding pin and pawl of the cap.

I claim:

The combination of a hub having a cylindrical extremity thereof provided with diametrically opposite outwardly open curvilinear peripheral grooves and similarly disposed peripheral racks, the grooves and racks being alternate about the hub; a cap 70 having inner pins engageable with the hub-grooves, spring-controlled pawls hung in inner recesses of the cap for engagement with the hub-racks, and a pivotal push-pin 75 extending from each pawl through a guide-aperture in said cap.

In testimony that I claim the foregoing I have hereunto set my hand at Hartford in the county of Washington and State of Wisconsin in the presence of two witnesses.

KNEELAND T. SIMONS.
